UNITED STATES PATENT OFFICE.

LEVI H. MANNING, OF TUCSON, ARIZONA.

PROCESS OF TREATING HYDROCARBON OILS.

Application filed April 16, 1921. Serial No. 461,994.

To all whom it may concern:

Be it known that I, LEVI H. MANNING, a citizen of the United States, residing at Tucson, in the county of Pima and State of Arizona, have invented certain new and useful Improvements in Processes of Treating Hydrocarbon Oils, of which the following is a specification.

This invention relates to a process for 10 heat treating hydrocarbon oils to obtain different materials, and in particular the process relates to details of operation by which low boiling hydrocarbon oils are formed from relatively high boiling petroleum oils.

15 The features of invention include details of a process of cracking petroleum oils which makes it possible to treat liquid oil to obtain lighter products without the usual trouble resulting from carbon deposits.

20 One particular feature provides for the treatment of liquid oil in such a way that carbon and heavy material is moved to points of relative quiet for removal, while the other portions of a mass of liquid oil 25 are subjected to a pulsating agitating movement within prescribed limits, as contrasted to a flowing movement, and at the same time that the portion undergoing agitation is subjected to a heat treatment. This feature also provides that no heat shall be applied to the portions not undergoing agitation nor to that part of the mass of oil which is relatively quiet.

The invention provides also for the continuous operation of the process and for the continuous introduction of untreated material and continuous withdrawal of material treated and produced. The process contemplates the use of positive cracking temperatures of at least 700° F., and pressures 40 above atmospheric pressure.

The details which make possible the particular movements of the material treated and the particular heat treatment applied 45 to particular portions of the material are intimately related and interdependent on apparatus which is described and claimed in the companion application Serial No. 461-995. Details of this apparatus provide for 50 the use of particular elliptically shaped discs or vanes mounted on a rotary shaft and arranged to revolve therewith within a tubular still which has a bore approximately that of the shorter diameter of the vanes. These peculiarly shaped vanes and 55 their mounting on the shaft make possible

the pulsating movement of the oil and also provide for the agitating movement in situ of cleaner members located between the vanes and propelled thereby. 60

In order that the process may be understood there is hereafter presented a description of the apparatus which has served to adequately perform the mechanical operations required. The above mentioned features of the process and additional features are described and claimed in the accompanying specification and claims, and the apparatus which serves to perform the steps of the process is illustrated in the accompanying drawings in which—

Figure 1 is a side elevation of the apparatus showing the relative position of the parts and indicating in dotted lines the relation of the furnace structure and heating means to the other portions of the apparatus; 75

Figure 2 is an enlarged view of one of the retort tubes, partly broken away and partly in section, showing the mounting of the vanes within the cracking tube and between the downwardly projecting pipes for the removal of solid material; 80

Figure 3 is an enlarged view of the side of one of the elliptical agitator scraper vanes; 85

Figure 4 is a front view taken axially of the vane shown in Figure 3;

Figure 5 is a view of the rotatable shaft removed from one of the treatment tubes and showing the splines which are adapted to engage the keyway of the vanes; 90

Figure 6 is a view of the vane shown in Figure 4 taken at right angles to the plane of the vane, and showing the elliptical contour of the periphery of the vanes. 95

Like reference characters indicate like parts in the various figures of the drawings.

Referring in detail to the construction illustrated in the drawings, 1 represents the masonry construction, either concrete, stone or brick, but preferably fire-brick, such as will stand severe temperatures. A suitable stack is provided for leading off the furnace fumes, smoke, and gases of combustion. A source of heat is provided by burners, not shown, located at the lower part of the furnace and supplied with liquid fuel by pipes 3 communicating with the point of removal of waste oil from the apparatus, as will be described. Individual branch pipes 3^a are connected with the burner supply pipes 100 105 110

3 and are provided with independent valves 3^b for regulating the supply of burning oil to the burners. An additional valve 3^c is located in the pipe 3 and may be used for regulating the use of either one of two burners and the connection between such burners and the branch pipes 3^a. The flames and hot gases from the burner nozzles are projected inwardly and passed upwardly 10 in the furnace to ultimately escape through the stack 2. During the upward movement, the heat comes into direct contact with the exterior of a plurality of longitudinally positioned retort tubes, as will be described.

15 The drawing illustrates two cracking tubes or retort tubes 4 and 5, positioned one above the other and substantially horizontally. The number of tubes might well be limited to one or increased to three or four, 20 providing the heating arrangements and mechanical features could be satisfactorily operated. Within the tubes 4 and 5 are the combined agitator scraper vanes or discs 4^a and 5^a, mounted on and adapted to turn 25 with their respective shafts 4^b and 5^b respectively. Suitable journal boxes or stuffing boxes are indicated for the respective shafts at 4^c and 5^c. The details of the construction and shape of the vanes constitute 30 an important feature of the present invention. Referring particularly to Figures 2, 3, 4 and 5, it will be noted that each vane is mounted on the shaft at an angle to the shaft and that each substantially fills the 35 bore of the cylindrical tube. Each vane is elliptical in shape and has substantially the same shape as that of an inclined section taken through the cylindrical tube within which it is mounted. Thus in Figure 6 40 there is shown the exact relative dimensions of the vane, and in Figure 4 the longer dimension is shortened, because the view is taken axially instead of at right angles as in Figure 6. Each vane has a hub portion 4^c having right angle shoulders 4^f which are 45 adapted to engage corresponding shoulders on adjacent vanes when the apparatus is in its assembled form. The shaft 4^b is provided with longitudinally extending splines 50 4^g adapted to engage the keyway slot or groove 4^h provided in the axial opening of the vanes. Each vane is also provided with a plurality of perforations 4ⁱ through which oil may be forced during the operation of 55 the apparatus, as will be described.

Referring to Figures 1 and 2, 6 indicates a communicating tube extending from the retort tube 4 to the retort tube 5 and located at the left side of the structure adjacent the 60 ends of the tubes. A similar communicating tube 6^a is provided adjacent the opposite ends of the tube. It will be observed that the agitating scraper vanes are not positioned opposite the communicating tubes 6 and 6^a. At the left hand end of the lower

tube 5 is a draw off pipe 7 for removing carbon and relatively heavy material which may be formed during the operation of the apparatus. A similar draw off pipe 7^a is provided at the opposite end of the lower 70 tube 5. Valves 8 and 8^a are provided on the respective pipes 7 and 7^a. The operation provides for the use of the heavy material which is withdrawn for fuel in the burners beneath the apparatus and to this end a 75 pipe 9 is connected to the pipes 7 and 7^a and conducts this fuel material to the burner supply pipe 3 and its branch pipe 3^a. Valves 9^a are provided for regulating the 80 admission of waste material from the pipes 7 and 7^a to the pipe 9.

At the top of the system of cracking tubes and above the furnace 1 is positioned a large reservoir or expansion chamber 10 which 85 communicates with the top of each end of the upper cracking tube 4 by means of the pipes 11 and 11^a leading from the lower side and opposite ends of the chamber 10. A series of test drain pipes provided with suitable valves are indicated at 10^a at different 90 elevations on the chamber to determine the height of oil therein and the nature of the oil at different heights. Additional means for determining the height of oil within the chamber is indicated at 10^b in which a float, 95 shown in dotted lines, within the chamber operates an indicating arrow on the outside of the chamber by means of a connecting lever. Oil is conducted from an oil tank or other suitable source of supply, not shown, 100 through the pipe 12 to a pump 13 which is adapted to force the oil against the pressure within the apparatus upwardly through the pipe 14, past the valve 15^a and through 105 the pipe 15 to the top of the expansion chamber 10, or directly into the communicating pipe 6 by being led into the pipe 16 past the valve 16^a. Operation of the valves 15^a and 16^a will regulate the point and 110 volume of the flow of untreated fresh oil through either one or both of the pipes 15 and 16, respectively. Immediately above the expansion chamber 10 are the upwardly extending vapor removing pipes 17, 17^a and 17^b which are connected to the pipe 18 by 115 means of a regulating valve 18^a, and all materials in an aeriform condition are led through the pipe 18 to a condenser, not shown. An additional pipe connection is indicated at 19 on the upper side of the expansion chamber 10 and may serve to connect the apparatus to any suitable reflux condenser, not shown.

Drive means for driving the shafts 4^b and 5^b is provided by a main drive belt 20 connected to any suitable source of power, not shown, and which passes over a pulley wheel 21 which is mounted to turn a shaft 22. A bevel gear 23 is mounted to rotate with the shaft 22 and is in mesh with a similar larger 120 125 130

bevel gear 24 mounted on a shaft 25 which latter is illustrated as substantially parallel to the retort tubes 4 and 5. A gear 26 is fixed to turn with the shaft 25 and is in 5 mesh with the gears 4^a and 5^a which are respectively fixed to rotate with the shafts 4^b and 5^b.

Within the retort tubes and positioned 10 between the parallel blades of the combined agitator and scraper vanes are metal balls 27 which remain in the retort tubes in their respective positions between the vanes and are moved back and forth in these fixed restricted locations during the 15 rotation of the vanes. Thus the balls have a movement in situ and are free to roll and tumble within prescribed limits, namely between adjacent vanes.

In the revolution of the shafts 4^b and 5^b 20 the movement of the vanes performs a function which is peculiar to the present invention. Referring particularly to the view in Figure 2, it will be noted that the space between A and D is scraped by the 25 vane connected by lines from these letters. Likewise, it will be noted that the lines from the letters B and D dropped from the extreme upper tips of the vanes which are adjacent pass through substantially the 30 center point of the vane next to the right, and that a line taken upwardly as from C from the lower tip of one vane is spaced slightly from the line taken from B and does not touch the upper tip of the second 35 vane to the left, and barely misses this second vane. In a single revolution of the shaft 4^b or 5^b with their respective vanes, that portion of the cylindrical inner wall of the cracking tubes within the space between 40 the lines A—B and C—D is scraped four times, and the portion between the lines B and C and the portion opposite the extreme tip of the vanes is scraped twice. This is made possible by the inclined overlapped position of the vanes, their close 45 parallel relation, and their particular elliptical shape. This multiple scraping action may be understood better by observing that the portions between A and B and between 50 C and D are engaged once by each of the two opposite sides of the vane, as for instance the points X and Y on the vane shown in Figure 6, and also by the corresponding points on the opposite end of the 55 vane next to the right, which opposite end is shown in Figure 2 as underlying the points X and Y.

The operation of the movement of oil 60 into and out of the apparatus, and the treatment of the fresh material within the retort cylinder tubes may be understood from the following description. Oil is introduced through the pipes 15 or 16 in sufficient quantity to have the retort tube in the 65 furnace preferably full of oil, and pref-

erably the oil is in sufficient quantity to substantially half fill the expansion chamber 10, which latter also serves as a reservoir. During the operation of the apparatus and the process which would be performed thereby, oil flows downward through the pipes 11 and 11^a and into the treatment tubes 4 and 5. The revolution of the agitating scraper vanes causes a pulsating movement of the oil back and forth and is to be contrasted to a conveyor action. It will be noted that the ends of the retort tubes are not provided with agitator scraper vanes and that these vanes do not extend over the openings of pipes 6 and 6^a, 7 and 7^a, but are positioned between such points. There is, therefore, a region of relative quiet in the oil at these points such as will permit the settling out of carbon and relatively heavy material formed during the retort and cracking treatment. At the same time it has been found that the agitation of the oil during the revolution of the vanes serves to keep any carbon formed in suspension in the oil, and to 85 pass such relatively solid material to points of relative quiet, that is to the ends of the tubes and to points adjacent the withdrawal pipes 6 and 6^a, and 7 and 7^a, down through which pipe openings the carbon and solid 90 material is permitted to gravitate to ultimately be withdrawn for use as fuel in the apparatus or for other treatment. It will be observed that the operation provides an unusually efficient scraping action without 95 requiring any conveying action of the oil through the treatment tubes, and this combined agitation and scraping movement is believed to be one explanation of the unusually satisfactory results which the invention 100 has made possible. The openings in the agitator scraper vanes permit the escape of portions of the oil endwise in the tubes, and this may explain the performance by which the carbon is permitted to escape 105 with the oil to the space at the ends of the tubes and to settle at these points of relative quiet. The presence of the balls, preferably steel balls, 27 assists in cutting carbon formations from the interior of the 110 cylinder walls and also from the surface of the agitator scraper vanes. The combined action of the agitator is thus to scrape the interior of the tube walls and also to serve the function of keeping the carbon and 115 heavy material in suspension until it reaches the points of rest and relative quiet in the region of the outlet pipes.

The continuous operation provides for the 120 constant removal of aeriform material from the upper side of the expansion chamber and discharge of such material through the pipe 18 to a condenser, and during this movement a continuous withdrawal of carbon and heavy 125 material which constantly settles in the 130

region of quiet above the ends of the withdrawal pipes 7 and 7^a. The rate of withdrawal of aeriform material and of waste material, and the rate of introduction of heat treated oil is dependent on the size of the apparatus and the relative production as result of a particular temperature treatment, pressure and atmospheric conditions. The valves governing the inlet and outlet pipes may therefore be adjusted to suit such conditions.

The process has been satisfactorily conducted in a plant having a construction similar to that illustrated in the drawings, in which plant the retort tubes were ten feet long and the bore of which was approximately six inches. The vanes substantially filled this bore and had a close fitting engagement with the tube walls which was sufficient to provide a positive scraping action, but not sufficient to bind the vanes and hinder the revolution of the shaft. In this operation the shafts with the agitating scraper members were revolved at speeds ranging up to seventy-five revolutions per minute, and the oil treated was thus subjected to a very severe agitation. The invention provides for cracking and the production of light materials from relatively heavy, and has operated satisfactorily at temperatures ranging from 700° F. upward in treating California oils of various qualities. By providing for the application of heat to those portions only where there was a scraping and agitating action it has been possible to permit the settling action of the relatively heavy material without incurring carbon formation in the region of such settling.

I claim:—

1. The process of treating hydrocarbon oils which process comprises subjecting the oil to be treated to a continuous agitating movement within a normally stationary and closed chamber and to contact with freely movable metallic elements propelled within prescribed limits in said chamber, and subjecting said oil while in said chamber to a heat treatment applied to the exterior of the chamber.

2. The process of treating hydrocarbon oils which process comprises subjecting the oil to be treated to a continuous agitating movement within a closed tubular chamber, causing an agitator member within said chamber to move said oil and propel freely movable metallic balls within prescribed limits in contact with said oil, and subjecting said oil while in said chamber to a heat treatment applied to the exterior of the chamber.

3. The process of treating hydrocarbon oils which process comprises subjecting the oil to be treated to a continuous agitating movement within a normally stationary and

closed chamber and to contact with freely movable non-absorbent elements having high heat conductivity propelled within prescribed limits in said chamber, and subjecting said oil and freely movable elements while in said chamber to a heat treatment applied to the exterior of the chamber.

4. The process of treating hydrocarbon oils which process comprises introducing oil to be treated into a closed substantially horizontal elongated tubular treatment chamber, applying heat to a portion of the length of said chamber but not to another portion, subjecting said oil within said chamber at that portion only to which heat is applied to a positive agitating movement during the heat treatment, continuously causing carbon formed in the heated portion to be removed from the heated portion and to be passed to the unheated portion and out of the region of agitation, and withdrawing the carbon and relatively heavy material resultant of the heat treatment from the unheated portion of said chamber.

5. The process of treating hydrocarbon oils which process comprises introducing oil to be treated into a closed substantially horizontal elongated tubular treatment chamber, applying heat to a portion of the length of said chamber but not to another portion, subjecting said oil within said chamber at that portion only to which heat is applied to a positive pulsating agitating movement which causes the liquid to take a movement in situ and causes the carbon and solid particles to be passed to relatively quiet and unheated portions of said oil, and withdrawing the carbon and relatively heavy material resultant of the heat treatment from the unheated portion of said chamber.

6. The process of treating hydrocarbon oils which process comprises introducing oil to be treated into a closed substantially horizontal elongated tubular treatment chamber, applying heat to a portion of the length of said chamber, subjecting said oil within said chamber to a positive agitating movement applied to only a portion of the oil in the length of said chamber, continuously causing carbon formed during the heat treatment to be passed to the part of said chamber containing oil not directly subjected to agitation continuously permitting the carbon to settle to a level below the level of the heated portion of the chamber, and withdrawing the carbon and relatively heavy material thus segregated.

7. The process of treating hydrocarbon oils which process comprises introducing oil to be treated into a closed substantially horizontal elongated tubular treatment chamber, applying heat to a portion of the length of said chamber, subjecting said oil within said chamber to a positive pulsating agitating movement applied to only a portion of

the oil in the length of said chamber, which movement causes the liquid to take a pulsating movement in situ and causes the carbon and solid particles to be passed to relatively quiet portions of the oil in said chamber, and withdrawing the carbon and solid particles thus segregated.

8. The process of producing hydrocarbon oils having low boiling points from hydrocarbon oils having high boiling points which process comprises subjecting the oil to be treated to a continuous agitating movement within a normally stationary and closed chamber and to contact with freely movable metallic elements propelled within prescribed limits in said chamber, and subjecting said oil while in said chamber to a temperature of at least 700° F. applied to the exterior of the chamber.
10. 9. The process of producing hydrocarbon oils having low boiling points from hydrocarbon oils having high boiling points which process comprises subjecting the oil to be treated to a continuous agitating movement within a closed tubular chamber, causing an agitator member within said chamber to move said oil and propel freely movable metallic balls within prescribed limits in contact with said oil, and subjecting said oil while in said chamber to a heat treatment of at least 700° F. applied to the exterior of the chamber.

10. The process of producing hydrocarbon oils having low boiling points from hydrocarbon oils having high boiling points which process comprises subjecting the oil to be treated to a continuous agitating movement within a normally stationary and closed chamber and to contact with freely movable non-absorbent elements having high heat conductivity propelled within prescribed limits in said chamber, and subjecting said oil and freely movable elements while in said chamber to a heat treatment of at least 700° F. applied to the exterior of the chamber.

11. The process of producing hydrocarbon oils having low boiling points from hydrocarbon oils having high boiling points which process comprises subjecting the oil to be treated to a pulsating agitating movement lengthwise within a closed tubular container, and subjecting said oil to a heat treatment of at least 700° F. applied directly to the exterior of said container.

12. The process of producing hydrocarbon oils having low boiling points from hydrocarbon oils having high boiling points which process comprises introducing oil to be treated into a closed substantially horizontal elongated tubular treatment chamber, applying heat to a portion of the length of said chamber but not to another portion thereof sufficient to heat the oil content of the chamber to at least 700° F., subjecting

said oil within said chamber at that portion only to which heat is applied to a positive agitating movement during the heat treatment, continuously causing carbon formed in the heated portion to be passed to the unheated portion and out of the region of agitation and withdrawing the carbon and relatively heavy material resultant of the heat treatment from the unheated portion of said chamber by continuously permitting the carbon to settle to a level below the level of the heated portion of the chamber.

13. The process of producing hydrocarbon oils having low boiling points from hydrocarbon oils having high boiling points which process comprises introducing oil to be treated into a closed substantially horizontal elongated tubular treatment chamber, applying heat to a portion of the length of said chamber but not to another portion thereof sufficient to heat the oil content of the chamber to at least 700° F., subjecting said oil within said chamber at that portion only to which heat is applied to a positive pulsating agitating movement which causes the liquid to take a movement in situ and causes the carbon and solid particles to be passed to relatively quiet and unheated portions of said oil, and withdrawing the carbon and relatively heavy material resultant of the heat treatment from the unheated portion of said chamber.

14. The process of producing hydrocarbon oils having low boiling points from hydrocarbon oils having high boiling points which process comprises introducing oil to be treated into a closed substantially horizontal elongated tubular treatment chamber, applying heat to a portion of the length of said chamber, the temperature of said heat treatment being sufficient to raise the oil within the chamber to a temperature of at least 700° F., subjecting said oil within said chamber to a positive agitating movement applied to only a portion of the oil in the length of said chamber, continuously causing carbon formed during the heat treatment to be passed to the part of said chamber containing oil not directly subjected to agitation, continuously permitting the carbon to settle to a level below the level of the heated portion of the chamber and withdrawing the carbon and relatively heavy material thus segregated.

15. The process of producing hydrocarbon oils having low boiling points from hydrocarbon oils having high boiling points which process comprises introducing oil to be treated into a closed substantially horizontal elongated tubular treatment chamber, applying heat to a portion of the length of said chamber, the temperature of said heat treatment being sufficient to raise the oil within the chamber to a temperature of at least 700° F., subjecting said oil within said

chamber to a positive pulsating agitating movement applied to only a portion of the oil in the length of said chamber, which movement causes the liquid to take a pulsating movement in situ and causes the carbon and solid particles to be passed to relatively quiet portions of the oil in said chamber, and withdrawing the carbon and solid particles thus segregated.

10 16. The process of treating hydrocarbon oils which process comprises continuously introducing oil to be treated into a closed container, continuously subjecting the oil material thus introduced to a pulsating agitating movement within said container and in the direction of the path of flow from the inlet to the outlet, applying heat to the exterior of a portion only of said container, and continuously withdrawing aeriform material from the top of said container and continuously withdrawing carbon and relatively heavy material from the lower side of said container.

15 17. The process of treating hydrocarbon oils which process comprises continuously introducing oil to be treated into a closed tubular container, continuously subjecting the oil material thus introduced to a pulsating agitating movement lengthwise within

said container and to a continuous scraping movement on the inner surface of the walls of the container, applying heat directly to the exterior of that portion of the container which is scraped on the inside, continuously permitting the carbon to settle to a level below the level of the heated portion of the chamber and continuously withdrawing aeriform material from the top of said container and continuously withdrawing carbon and relatively heavy material from the lower side of said container.

18. The process of treating hydrocarbon oils which process comprises continuously introducing oil to be treated into a closed container, continuously subjecting the oil material to a travelling movement through the container and at the same time subjecting said oil material while in its travelling movement to a pulsating agitating movement and in the direction of the path of flow from the inlet to the outlet, applying heat to that portion of the container within which the agitating movement takes place, and continuously withdrawing carbon and relatively heavy material from the lower side of said container.

In testimony whereof I affix my signature.
LEVI H. MANNING.
